KOREAN TYPEWRITER

Pyung Woo Kong, Seoul, Korea

Application July 8, 1949, Serial No. 103,570
In Korea May 18, 1948

2 Claims. (Cl. 197—1)

1

This invention relates to a typewriting machine for therewith writing in Korean language. Several machines for this purpose have been heretofore proposed and made, which are however deemed disadvantageous by those familiar with that language and its typewriting requirements, in that they were too complicated, unreliable in performance, too costly to manufacture, of high cost to the user, and impractical as well as unsatisfactory in the mode of presenting the written language. Various other serious objections are inherent in the said machines, as is well known to those familiar with the language and their uses and operations.

The principal object of the invention is to provide an improved Korean language typewriter, which will remedy all and other of the aforesaid disadvantages and objections, and be furthermore simplified, conveniently and economically manufacturable, salable at low cost, strong, rigid, durable, reliable, efficient, conveniently utilizable, and capable of writing the language in a mode as required and acceptable by those familiar with it.

Another object is to provide an improved Korean language typewriter which will possess all of the aforesaid advantages of the invention, and utilize substantially all and identical parts, features, and operations of the conventional American machine, whereby the typewriter may be manufactured with ease, convenience, economy, and resort to the already existing facilities of the manufacturer of such machines, and hence resulting in low purchase price to the consumer.

Other objects and advantages will hereinafter appear.

In the accompanying drawings,

Fig. 1 is a diagrammatic elevational view of a type writing machine embodying the invention.

Fig. 2 is a fragmentary diagrammatic plan view of the machine shown in Fig. 1.

Fig. 3 is a fragmentary plan view illustrating the focal guiding device of the invention.

Fig. 4 is a diagrammatic plan view illustrating the keyboard of the invention.

Fig. 5 shows a Korean language phrase as written on the machine of the invention.

Fig. 6 illustrates the Korean language writing symbols.

The type writing machine 1, Figs. 1 and 2, embodies a series of bars 2 carrying types 3, each of said bars being pivoted at 4 and having in turn pivoted thereto at 5 a link 6 which is pivoted at 7 to a lever 8. Each of the levers 8 is pivoted at 9, carries a key 10, and a spring 11 normally draws

2

the lever to an inoperative position and thereby maintains its link 6 and type bar 2 in the inoperative state shown. Striking on any key 10 transmits swinging motion to its type 3 about pivot 4, and causes the type to strike an impression upon a platen 12 mounted on a carriage 13 of the machine 1. The machine 1 further embodies a lever plate 14 pivoted at 15, and a rod 16, pivoted to said plate at 17, passes through a plate 18, and carries at its terminal a head 19. Said plate 18 is pivoted at 20 and carries a pawl 21 which actuates mechanism 22 for advancing the carriage 13 in performance of the spacing function of the machine.

As seen in Fig. 4, the key board 23 of the machine comprises two clusters 10a, 10b of all keys 10. When any key 10 belonging to cluster 10b is struck its lever 8 strikes the plate 14, contrary to pressure of a spring 24, and causes it to actuate the mechanism 22, through movement of the rod 16, plate 18, and pawl 21, for advancing the carriage 13 with the platen 12, upon impression of the type 3 with said platen. When however any key 10 belonging to cluster 10a is struck, the striking part 8a of its lever 8 enters a gap 25 in the lever plate 14, and thereby leaves said plate unactuated and the carriage 13 with the platen 12 stationary upon impression of its type 3 with the platen.

As shown in Fig. 6, the used symbols 26 for writing the Korean language comprise four groups 27, 28, 29, 30, denominated pre-consonants, vowels, intermediate vowels, and sub-consonants respectively, the said groups including nineteen, fourteen, three, and twenty-seven symbols respectively, as illustrated. As seen in Fig. 5, the symbols 26 are used for composing characters, as 31, 31a, 31b, 31c, etc., any line or combination of such characters expressing a thought in the nature of a word, several words, a phrase, or sentence. For example, the illustrated characters in Fig. 5 are equivalent to the expression "He has come." The said characters are generally separated by spaces 32, though at times two may be written without separation. In the forming of any character, as those herein shown, the first written symbol is in all cases a pre-consonant or belonging to the group 27, Fig. 6, and with said symbol is combined one, two, or three more symbols 26 belonging to the remainder groups 28, 29, 30. For example, considering the character 31, Fig. 5, the first written symbol 26a, is a pre-consonant belonging to group 27, while the succeeding symbols 26b, 26c, 26d belong to the remaining groups 28, 29, 30.

In this machine, fig. 4, the keys 10 comprised in cluster 10a with their corresponding types 3, Fig. 1, carry the remainder of all symbols 26 belonging to the groups 28, 29, 30, while the keys comprised in cluster 10b with their types carry the pre-consonants or the symbols 26 belonging to group 27, as well as Arabic numbers with English punctuations and signs as illustrated.

The type guiding device 33, Fig. 3, of the machine is provided with two focal openings 34, 35, having the distance 36 between their centre lines 37 equal to the spacing distance of the platen 12. When any key 10 belonging to cluster 10b, Fig. 4, is struck, its type 3 is guided for impression upon the platen 12 by the opening 35, while the striking of any key belonging to the cluster 10a guides its type to the platen through the opening 34, the operation of the key of cluster 10b causing a space movement of the carriage 13 and platen 12, while striking the key of cluster 10a does not affect the carriage and platen, which thus remain stationary.

When it is desired to write any character, as 31, Fig. 5, the key 10c of cluster 10b is first struck, which causes the type of the pre-consonant 26a to be guided through the opening 35 for impression on the platen area opposite thereto and moves the platen 12 one space to bring said area into registry with the focal opening 34. The typist then strikes successively the keys 10d, 10e, 10f of cluster 10a, which operations cause the types of the remainder symbols 26b, 26c, 26d to strike the platen 12 through the focal opening 34 and write the said symbols in their appropriate relation shown in Fig. 5, while the platen remains stationary. The space bar 33, Fig. 2, may be then struck for normal advancement of the carriage, for creating the space 32, and the numbers, punctuations, and signs seen in Fig. 4 may be written on this machine by striking their keys in conventional manner.

Variations may be resorted to within the scope of the invention, and portions of the improvements may be used without others.

Having thus described my invention, I claim:

1. A typewriter for Korean language having the combination with a carriage, a platen on said carriage, a series of type bars, a series of corresponding keys for actuating said type bars, and mechanism for actuating said carriage, of a

first quantity of said bars carrying Korean pre-consonant types, said first bars directing their types to strike said platen at a first focus and being operated by a first cluster of keys, a second quantity of said bars carrying the remainder of Korean types, said second bars directing their types to strike said platen at a second focus leftwardly of said first focus and being operated by a second cluster of keys, a device providing a guiding opening for therethrough focusing said pre-consonant types, said device providing an additional opening leftwardly of said other opening for therethrough focusing said remainder types, means to cause said first cluster of keys of said pre-consonant types to operate said mechanism to actuate said carriage and platen, and means to cause said mechanism, carriage, and platen to remain stationary during operation of said second cluster of keys of said remainder types.

2. A typewriter for Korean language having the combination with a carriage, a platen on said carriage, a series of type bars, a series of corresponding keys for actuating said type bars, and mechanism for actuating said carriage, of a first quantity of said bars carrying Korean pre-consonant types, said first bars directing their types to strike said platen at a first focus and being operated by a first cluster of keys, a second quantity of said bars carrying the remainder of Korean types, said second bars directing their types to strike said platen at a second focus leftwardly of said first focus and being operated by a second cluster of keys, means to cause said first cluster of keys of said pre-consonant types to operate said mechanism to actuate said carriage and platen, and means to cause said mechanism, carriage, and platen to remain stationary during operation of said second cluster of keys of said remainder types.
